UNITED STATES PATENT OFFICE.

HARRY S. DOSH, OF BALTIMORE, MARYLAND, ASSIGNOR TO GEORGE F. OBRECHT AND GEORGE SCHEIHING, OF SAME PLACE.

ELECTRIC IGNITER FOR GAS-ENGINES.

SPECIFICATION forming part of Letters Patent No. 586,479, dated July 13, 1897.

Application filed February 17, 1897. Serial No. 623,781. (No model.)

To all whom it may concern:

Be it known that I, HARRY S. DOSH, of Baltimore city, in the State of Maryland, have invented a new and useful Improvement in Electric Igniting Devices for Gas-Engines, of which the following is a specification.

My invention is in the nature of an improved electric igniting device for exploding the mixture of air and gas in the cylinder of a gas-engine.

Electric igniters have heretofore been employed, but it has been necessary always to employ a heavy battery-power of from six to ten cells. I have devised a device whereby the electric igniter is made to operate successfully and with certainty and uniformity with a single battery-cell.

My invention is founded upon the following general principle and the observation of its application to a gas-engine—namely, that the electric spark meets with an increasing resistance in proportion to the density of the medium through which it passes—and I have found that the reason so heavy a battery-power is required in gas-engine igniters is because of the high pressure (sixty pounds) at which the gas and air are charged to the cylinder, which makes a medium so dense that a correspondingly greater battery-power is required to force the spark through this medium, which is rendered more non-conducting by its pressure and density.

My invention comprises a means of creating in the gas-cylinder a partial vacuum or reduced pressure between the spark electrodes and simultaneously transmitting through this more tenuous medium of gas and air the electric spark, which permits a very weak battery of a single cell to produce the igniting spark.

In carrying out my invention I construct the two electrodes or contact-pieces as flat disks or plates, which lie almost in contact, with only a small sheet of platinum in the center of one of them as the spark-discharging point, and provide means for jerking one or both of the plates away from the other so quickly as to produce a temporary suction between them that reduces the gas-pressure and its density, and thus increases the conductivity or reduces the resistance of the medium to such an extent as to permit a spark

from a relatively weak generator to ignite the gas, as hereinafter more fully described with reference to the drawings, in which—

Figure 1 is a front view of the igniter, 55 showing that part of it which is exposed to the air and gas in the cylinder. Fig. 2 is a back or outside view of the same; and Fig. 3 is a section of the same, showing its application to the end of the engine-cylinder. 60

In the drawings, A represents a plate having four holes a, by which it is bolted to the cylinder S, and having on its inner face an oblong projection A', that enters a slot of corresponding shape in the cylinder. In a 65 non-conducting bushing c in the plate there is fixed and thoroughly insulated from every metal part a bolt B, which has a head inside the cylinder insulated by non-conducting washers, and having a metal disk x, standing in a plane parallel to the axis of the bolt and constituting one of the electrodes or contact-points of the igniter. This bolt is secured by jam-nuts b b' within the plate A A', which nuts are insulated by non-conducting washers from the plate and receive and clamp the circuit-wire b² from the battery, the other circuit-wire being connected to any part of the metal of the cylinder or plate A. Just beside the disk x there is another one, y, mounted upon the end of a crank-arm D' on a rock-shaft D, passing through the plate A A' and also through a hub A³, formed on the outside of the plate. At one end the plate A is extended in the form of a curved arm 85 A², and has secured to it, by screws or bolts, flat springs E and F, which occupy positions upon the opposite sides of the arm A². On the outer end of the rock-shaft D (see Fig. 2) there is rigidly attached a crank-arm D², carrying at its outer end a cross-pin d, which lies between and is pressed upon from opposite sides by the free ends of the flat springs E F. 90

G is a tripping-bar which is given a longitudinally-reciprocating motion by any suitable part of the engine and whose function is to push back the spring E, then pass by its end, and allow it to fall with a sudden hammer-like blow on the pin d. To permit this action, the tripping-bar G has a hub g 100 playing between the lugs G² G³, cast on the frame-plate, and has an inclined surface that

bears upon the stationary incline G' on the frame-plate. Now when the tripping-bar is advanced it first strikes and lifts the spring E away from the pin d , and then its incline 5 hub g , striking against the inclined bearing G' , rides up thereon and causes the end g^2 of bar G to move sidewise, as shown by dotted lines, and allow the spring E to fly back, the momentum of the latter being increased by a 10 weight e on said spring. As the bar G moves back a spring g' brings its hub down again over the incline G' .

The operation of this device is as follows: The plates or disks x y , Fig. 1, constitute the 15 terminal contact-points of the battery and are normally out of contact with each other. When brought together they lie less than one-hundredth part of an inch apart, actual contact being made at the proper time by a 20 thin platinum face z on the disk y touching the other disk x . Now when tripping-bar G advances its first action, as before stated, is to lift spring E. The pin d , now being pressed upon by the spring F only, yields 25 to this pressure and turns crank D^2 , rock-shaft D, and arm D' until the disk y and contact-face z are brought momentarily in contact with the other terminal disk x . Then as the end g^2 of the bar G slips off the end of 30 spring E the spring E strikes a hammer-like blow on the pin d , quickly deflecting crank-arm D^2 and the longer crank-arm D' on the other end of shaft D, which jerks the disk y away from contact with x with such suddenness as to produce a partial vacuum or 35 reduced pressure between them, and simultaneously with this action the spark passes from the platinum face z to disk x , directly through the center of the temporarily rarefied 40 body of air and gas, which permits of an igniting spark to be certainly and uniformly obtained with a single battery-cell.

Having thus described my invention, what I claim as new, and desire to secure by Letters 45 Patent, is—

1. An electric igniter comprising two electrodes having their ends formed as extended plates, and means for suddenly separating the plates, said plates lying sufficiently close together to cause by their separation a rarefaction of the gaseous medium between them substantially as and for the purpose set forth.

2. In an electric igniter the combination of a base-plate, an insulated terminal contact 55 arranged on the plate and in the cylinder, a rock-shaft journaled in the plate and having a radial arm with another terminal contact

within the cylinder, and a crank-arm outside the cylinder, a spring acting on this external crank-arm to rock the shaft and close the 60 contacts within the cylinder, and a separate spring acting upon the said external crank-arm in opposition to the first-named spring, and means for snapping said second spring against the external crank-arm to separate the 65 contacts with a hammer blow substantially as and for the purpose described.

3. A spark-making device for an electric igniter for gas-engines, comprising a base-plate, an insulated terminal contact arranged 70 within the plate, a rock-shaft journaled in the plate and having a radial arm with terminal contact-face and a shorter crank-arm on the other end, opposing springs acting upon opposite sides of the said short crank-arm, and a 75 tripping device for one of said springs substantially as and for the purpose described.

4. The electric igniter consisting of the combination of the base-plate A, insulated bolt B with terminal contact x , rock-shaft D 80 with crank-arm D' and terminal contact y on one end and a short crank-arm D^2 with pin d on the other end, the opposing springs E and F bearing upon opposite ends of the pin, the tripping-rod G with inclined face hub or collar g , the inclined bearing G' , and spring g' substantially as and for the purpose described.

5. In an electric igniter, the plate A having hollow hub A^3 and arm A^2 ; in combination with the insulated bolt with terminal contact, 90 the rock-shaft D with crank-arms on opposite ends, the springs E F mounted on the arm A^2 upon opposite sides of the rock-shaft and arranged to act against the external crank-arm, and means for operating the springs E with 95 a hammer blow substantially as and for the purpose described.

6. In an electric igniter, the plate A having hollow hub A^3 , arm A^2 and guide-lugs G^2 G^3 having inclined face G' ; in combination with 100 the insulated bolt with terminal contact, the rock-shaft D with crank-arms on opposite ends, the springs E F mounted on the arm A^2 upon opposite sides of the rock-shaft and arranged to act against the external crank-arm, 105 and the sliding rod G with inclined hub g and spring g' arranged between the lugs G^2 G^3 and acting against the spring E substantially as and for the purpose described.
